UNITED STATES PATENT OFFICE.

LOUIS L. RUPP, OF NEW YORK, N. Y.

DESIGN FOR TRIMMING.

SPECIFICATION forming part of Design No. 29,007, dated July 5, 1898.

Application filed June 13, 1898. Serial No. 683,367. Term of patent 7 years.

To all whom it may concern:

Be it known that I, LOUIS L. RUPP, of the city of New York, (borough of Manhattan,) in the county and State of New York, have 5 invented and produced a new and original Design for a Trimming, of which the following is a full, clear, and exact specification.

Reference is to be had to the accompanying drawing, forming a part of this specification, 10 in which the figure is a plan view of a trimming, showing my design.

The design consists of a series of parallel-spaced strands A, interwoven with crossing strands B and forming the body of the fabric, 15 with festoons C overhanging or appearing in front of the strands A and interlooped at

the beginning of the festoons with the crossing strands B, adjacent festoons crossing each other. Some of the festoons C appear in plain strands, while others, as at C', appear 20 in the form of a strand wound spirally on a core.

The leading feature of my design consists of festoons appearing on the face of the body of the fabric. 25

I claim—

The design for a trimming, as herein shown and described.

LOUIS L. RUPP.
